UNITED STATES PATENT OFFICE.

ERNEST HENRY METCALF, OF BRIDGEPORT, CONNECTICUT.

HAND-WHEEL.

SPECIFICATION forming part of Letters Patent No. 751,533, dated February 9, 1904.

Application filed May 27, 1903. Serial No. 158,972. (No model.)

To all whom it may concern:

Be it known that I, ERNEST HENRY METCALF, a citizen of the United States, and a resident of Bridgeport, in the county of Fairfield 5 and State of Connecticut, have invented a new and Improved Hand-Wheel, of which the following is a full, clear, and exact description.

This invention relates to a class of metal hand-wheels having tubular skeleton rims that 10 remain cool when mounted on a valve that in service becomes hot.

The object of my invention is to provide novel details of construction for a hand-wheel of the class indicated which may be generally employed, that will remain cool, be capable of rapid production, be very strong and durable, and inexpensive to manufacture.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a side view of the complete hand-wheel. Fig. 2 is a transverse sectional view substantially on the line 2 2 in Fig. 1. Fig. 3 is a plan view of a blank cut into shape from 30 sheet metal and from which is formed the skeleton wheel-rim. Fig. 4 is a side view of one of the reinforcing-disks that form the side walls of the hand-wheels. Fig. 5 is a transverse sectional view substantially on the line 35 5 5 in Fig. 4, and Fig. 6 is a side view of a filling-block employed as a body-piece for the hand-wheel.

In Fig. 3 the preferred form of the blank that when suitably bent comprises the skeleton wheel-rim 10 is shown consisting, essentially, of an oblong flat plate of metal which is rectangular, peripherally considered, and having formed at diagonally opposite corners the two similar integral dovetail tongues 40 c. In the material of the blank a series of slots a is formed, these slots being evenly spaced apart by the intervening bars a', these slots and bars extending throughout the area of the blank, considered longitudinally. As

shown, the slots a are of such a length as to 50 permit bars b to remain one at each side of the blank, said side bars of equal width being integral with the cross-bars a'.

In the formation of a wheel-rim 10 from the flat blank that has been described it is first 55 given tubular form, so as to cause the side bars b to nearly contact edgewise. Then said side bars are bent laterally, where they join the cross-bars a', so as to dispose them parallel and in contact with each other. 60

The side bars b are now curved together edgewise into circular form, which will dispose the cross-bars a' radially and separate them equally, thus forming a skeleton tubular rim. 65

In the formation of the rim 10 the dovetail tongues c are brought together and lapped upon each other, so that their edges conform, and these laterally-contacting tongues c c are projected inwardly, as is shown by dotted 70 lines in Fig. 1.

The filling-block 11 is in the form of a circular planchet and, as shown in Fig. 6, a dovetail notch c' is produced in the periphery thereof, the filling-block also having three 75 spaced perforations d and a central angular hole e formed therein. The diameter of the flat filling-block 11 is such as adapts it to fit neatly in the circularly-edged opening defined by the inner edges of the circularly-bent bars 80 b, and when the block is placed therein the lapped tongues c are inserted into the dovetail notch c', which holds the tubular rim 10 in place on the filling-block, so as to prevent its rotatable movement thereon. 85

Two similar clamping-plates 12 are provided as the side walls for the hand-wheel, each of said plates being cut from sheet metal and struck by suitable dies into the form shown. In Figs. 4 and 5 it will be seen that the clamping-plates 12 are each peripherally circular and are dished somewhat, projecting an annular flange g laterally therefrom. The flange g is concaved on its exterior surface and also is indented, cut, or nicked at suitable points 90 95 equally distant from each other, thus producing a continuous series of undulations that extend throughout the area of the flange and af-

ford equally-spaced projections h on the concaved surface of said flange.

The pair of clamping-plates 12 are of such relative diameter as to adapt them to fit oppositely upon the tubular body of the skeleton wheel-rim 10, the spaced projections h fitting between adjacent bars a' of said rim. Three perforations d' are formed in the flat portions of the clamping-plates 12, said perforations being so positioned that when the plates are in place on the sides of the filling-block 11 these perforations in the clamping-plates will be disposed opposite the perforations d in the filling-block, so that a rivet or bolt may be inserted through each set of aligned perforations.

Each clamping-plate 12 is centrally apertured at e' , these apertures having like angular form to that of the central hole e in the filling-block 11 and conform therewith when the plates 12 are secured upon the filling-block by means of the rivets i , that draw the plates firmly against the opposite sides of the wheel-rim 10.

When the parts of the hand-wheel are assembled and secured together as described, the projections h will be embedded between adjacent pairs of the spaced bars a' on the rim 10 and afford lateral support thereto, thus rendering the hand-wheel as an entirety very light, strong, and durable and adapted to keep measurably cool when mounted on a valve-stem for operation of the valve that in service is highly heated, it being obvious that the central holes e e' in the filling-block and clamping-plates are designed to receive the

end of the valve-stem whereon the hand-wheel is to be secured.

Having thus described my invention, I claim as new and desire to secure by Letters Patent—

1. A hand-wheel comprising a skeleton tubular rim, having an inwardly-projecting circular flange, a central filling-block whereon the rim is mounted, means for holding the rim from turning on the periphery of the filling-block, and two clamping-disks securable on the rim and filling-block. 45

2. A hand-wheel comprising a skeleton tubular rim having an inwardly-projecting circular flange, a dovetail tongue projected inward from said flange, a circularly-edged flat filling-block having a dovetail notch that receives the tongue when the rim is mounted on the filling-block, two similar clamping-plates, each having an annular peripheral flange that projects laterally and outwardly, said flange being concaved on its outer surface, and formed with spaced projections that enter between the bars on the rim for their lateral support, and means for securing the clamping-plates on the rim and filling-block, said plates and the filling-block having a central perforation. 50

In testimony whereof I have signed my name to this specification in the presence of two subscribing witnesses.

ERNEST HENRY METCALF.
